US0D1048520S

(12) **United States Design Patent** (10) **Patent No.:** **US D1,048,520 S**
(45) **Date of Patent:** ** *Oct. 22, 2024

(54) **ULTRAVIOLET LAMP**

(71) Applicant: **CE LIGHTING LTD.**, Shenzhen (CN)

(72) Inventor: **Dangwei Yang**, Shenzhen (CN)

(73) Assignee: **CE LIGHTING LTD.**, Shenzhen (CN)

(*) Notice: This patent is subject to a terminal disclaimer.

(**) Term: **15 Years**

(21) Appl. No.: **29/758,334**

(22) Filed: **Nov. 13, 2020**

(30) **Foreign Application Priority Data**

Jul. 23, 2020 (CN) 202030412543.0

(57) **CLAIM**

The ornamental design for an ultraviolet lamp as shown and described.

DESCRIPTION

FIG. 1 is a front elevational view of a ultraviolet lamp showing my new design;

FIG. 2 is a rear side elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a top perspective thereof.

The broken lines are shown for the purpose of illustrating parts of the article that form no part of the claimed design.

1 Claim, 7 Drawing Sheets
